(57) CLAIM

The ornamental design for a pillow holder for cell phones and tablets, as shown and described.

DESCRIPTION

FIG. 1 is a perspective view of a first embodiment of a pillow holder for cell phones and tablets showing our present design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is another perspective view of FIG. 1 with environment shown in broken lines.

FIG. 9 is a perspective view of a second embodiment of a pillow holder for cell phones and tablets showing our present design;

FIG. 10 is a front view thereof;

FIG. 11 is a rear view thereof;

FIG. 12 is a left side view thereof;

FIG. 13 is a right side view thereof;

FIG. 14 is a top view thereof;

FIG. 15 is a bottom view thereof;

FIG. 16 is another perspective view of FIG. 9 with environment shown in broken lines.

FIG. 17 is a perspective view of a third embodiment of a pillow holder for cell phones and tablets showing our present design;

FIG. 18 is a front view thereof;

FIG. 19 is a rear view thereof;

FIG. 20 is a left side view thereof;

FIG. 21 is a right side view thereof;

FIG. 22 is a top view thereof;

FIG. 23 is a bottom view thereof; and,

FIG. 24 is another perspective view of FIG. 17 with environment shown in broken lines.

The lower opacity portions bound by broken lines in the drawings indicate environment that forms no part of the claimed design.
